UNITED STATES PATENT OFFICE.

LEO EINSON, OF BROOKLYN, NEW YORK, ASSIGNOR TO EINSON-FREEMAN CO., INC., A CORPORATION OF NEW YORK.

COMBINATION PACKING AND DISPLAY CONTAINER.

Application filed July 14, 1926. Serial No. 122,312.

My invention relates to packing and display containers in which medium or small articles, either breakable or unbreakable, can be conveniently and quickly packed for shipment by the manufacturer and which may be opened by the retailer to display its contents in a convenient and attractive manner without injury to the container.

One of the objects of my invention is to provide a packing container which will be simple in construction and inexpensive to manufacture, and which when opened becomes a self-supporting display device which will be attractive in appearance for counter or wall display of the articles packed therein.

Another object of my invention is to provide a combination packing and display container which is divided longitudinally into two compartments by a vertical partition which is of such proportion to extend upward above the container to display advertising matter, and which, when properly folded down, entirely covers and protects the articles in the front or display compartment.

Another object of my invention is to provide a combination packing and display container of two compartments, namely a display compartment and a reserve compartment; the dividing partition forming these compartments being a cover for the former when folded down and having means for holding it in a vertical position when opened to display the articles packed therein, said means being in the form of end pieces or wings which fold backward causing the reserve compartment to be invisible to the vende.

A further object of my invention is to provide a combination packing and display container comprising display and reserve compartments; the front of the former being so cut and formed so as to fold inward on a horizontal plane to form an aligning member for the articles in both compartments.

With these and other objects in view, to be more fully set forth hereinafter, the invention consists in the novel construction, combination of elements and arrangements of parts which will be exemplified in the construction herein described in the following specification and illustrated in the accompanying drawings.

The disclosure made the basis of exemplifying the present inventive concept suggests a practical embodiment thereof, but the in-

vention is not to be restricted to the exact details of this disclosure, and the latter, therefore, is to be understood from an illustrative, rather than a restrictive standpoint.

The invention will first be described in connection with the accompanying drawings, wherein similar reference characters are used to designate corresponding parts throughout the several views, and more specifically defined and indicated in the appended claims.

Attention is directed to the drawings in which:

Fig. 1 is a front elevation of my combination packing and display container with the cover held in a vertical position to display advertising matter and to present to view for the purpose of display the front row of articles packed therein;

Fig. 2 is an end elevation of same;

Fig. 3 is a plan view of same;

Fig. 4 is a prospective view illustrating how the cover is folded down over the articles in the display compartment to protect them during their transition from the manufacturer to the retailer;

Fig. 5 is a greatly reduced view of the development of that portion of my container which forms the bottom, sides, aligning portion and cover for the reserve compartment;

Fig. 6 is a greatly reduced view of the development of that portion which forms the dividing partition for the display and reserve compartments and the cover for said display compartment; and

Fig. 7 is a greatly reduced side view of one of the pieces which divide the display and reserve compartments into individual stalls for each article packed in the container.

The body portion of my combination packing and display container consists of one sheet of material such as heavy paper or cardboard and comprises the ends 1 and 2, the front and rear portions 3 and 4 respectively, the aligning portion 5, the bottom 6 and the reserve compartment cover 7. (See Fig. 5). To form the body portion, the ends 1 and 2 and the front and rear portion, 3 and 4 are first bent at right angles to one another on the scored lines 8, 9 and 10 which define them. The gluing tab 11, defined by the scored line 12 and integral with the end 1, is then glued to the inner surface of the rear portion 4 causing the sides to take a rectangular form. The tabs 13 and 14, defined by the scored lines 15 and 16 integral with the ends 11,

1 and 2 respectively are then bent inward and the bottom 6 is also bent inward over them on the scored line 17 which defines it. The split tab 18 integral with the bottom 5 6 and defined by the scored line 19 is bent upward and rests against the inner surface of the rear portion 3. The bottom locking tab 20, also integral with the bottom 6 and defined by the scored line 19, is also bent upward but on the outside of the rear portion and is caused to enter the slot 21 cut in the rear portion for that purpose, the rounded out portion 22 of the locking tab hooking over the lower edge of the slot, thereby creating an effective lock to prevent the bottom from falling out during transit or when on display. The next operation is to bend the aligning portion 5 inward on the scored line 23 and bend the aligning portion support 24 downward on the scored line 25 which defines it. This support rests against the bottom, holding the aligning portion in a horizontal plane. The elongated openings 26 cut into the aligning portion are of such proportion to allow the lower ends of the articles 27, illustrated in dot and dash lines (Figs. 1 and 2), to pass through them to prevent their moving toward the sides and coming into contact with each other during shipment.

When the body portion has been formed as just described the next operation is to place the piece in position that forms the dividing partition for the display and reserve compartments and the cover for the former. The first step necessary in this operation is to place the partition pieces 28 in position in the slots 29 cut into the dividing partition 30. These pieces form the individual stalls for the articles which are to be packed. This is accomplished by forcing the partition pieces 28 upward at right angles to the dividing partition until the bottom 31 of the openings 32 reach the ends of the slots 29 as illustrated in Figs. 1, 2 and 3. The object of the opening 32 is to eliminate the necessity of running the slots 29 up to the scored line 33 which would materially weaken the dividing partition. With the pieces 28 in position the dividing partition is inserted vertically into the body portion until the shoulders 34 of the openings 35 rest upon the material 36 left between the elongated openings 26; the tabs 37 formed by the openings 35 passing down through the elongated openings as illustrated most clearly in Figs. 1 and 2.

The articles to be shipped and displayed are then placed in position and the tabs 38 and 39 integral with the ends 1 and 2 respectively are bent inward on the scored lines 40 and 41, and then the reserve compartment cover 7 is bent inward over them on the scored line 42. The end tab 43 of the cover 65 7 is bent downward on the scored line 44

which defines it, and as the cover is brought into its closed position it presses against the rear face of the dividing partition 30 (see Fig. 2) and holds said cover in the closed position. The aperture 45 in the cover 7 is provided to afford means for raising the cover when the container has been opened and placed on display.

To cover the row of articles in the display compartment, the first step necessary in this operation is to bend the end or wing portions 46 and 47 backward upon the top cover 48 and the front cover 49 on the scored lines 50 and 51 respectively. The top cover is then bent forward on the scored line 33 over the tops of the articles and the front cover 49 is bent downward on the scored line 52 as illustrated in Fig. 4. This downward bending of the front cover is facilitated by the apertures 53 as the double bending of two thicknesses of material at the point of intersection of the scored lines 50 and 52 would not permit a sharp corner to be made or would cause a rupture of the material at this point.

When the container is opened for display 90 the wings 46 and 47 are swung outward at right angles to the covers 48 and 49 and the locking tabs 54 and 55 located at the lower ends of the wings are caused to enter the curved slots 56 and 57 cut in the ends 1 and 2 95 respectively; the tabs hooking under the upper edge of the slot thereby holding the covers 48 and 49 in an upright position as illustrated in Figs. 1 and 2 to display the row of articles in front of them and to display advertising matter. The front cover 49 100 may have an ornamental contour to conform with the advertising matter printed upon it.

As the articles in the display compartment are sold they are replaced by those in the 105 reserve compartment which is invisible to the vendee. This eliminates the unsightly appearance of a display container with a number of vacant spaces until fifty per cent of the articles have been sold or the reserve may be replenished from another container which would eliminate the possibility of a vacant space while the articles are displayed.

The apertures 58 cut in the rear portion 110 have been provided to afford means for hanging the container upon a wall where it is not convenient to place it upon a counter. The apertures are of such proportion to allow the heads of nails, screws, hooks or any other suitable means upon which it can be hung 115 to pass through, clearance for said heads being provided by the cut-out 59 in the rear edge of the dividing pieces 28 (Fig. 7).

In Fig. 5 I have illustrated the cover 7 as being integral with the back 4. I wish it 120 distinctly understood that I do not so limit my invention as it is obvious that the cover 7 can be separately made.

In accordance with the provisions of the patent statute, I have described my inven- 125

tion, but I desire it understood that it is not confined to the particular form shown and described, the same being merely illustrative, and that the invention can be carried out in other ways without departing from the spirit of my invention, and therefore I claim broadly the right to employ all equivalent instrumentalities coming within the scope of the appended claims, and by means of which, 10 objects of my invention are attained and new results accomplished; as it is obvious that the particular embodiments herein shown and described are only some of many that can be employed to attain these objects and accomplish these results.

Having described my invention, what I claim and desire to secure by Letters Patent, is:—

1. A combination packing and display container consisting of a body portion, a vertical partition dividing said body portion longitudinally into a display compartment and a reserve compartment, an aligning panel formed of a cut-out and perforated portion 25 of one side of said display compartment, a cover for said display compartment integral with said vertical partition and a cover for said reserve compartment integral with a single sheet of material forming said body portion.

2. A combination packing and display container consisting of a body portion, a vertical partition dividing said body portion longitudinally into a display compartment and a reserve compartment, an aligning member integral with and composed of a cut-out and perforated portion of the front of said display compartment adapted to be bent inward to align the articles packed in both of said compartments, a cover for said display compartment integral with said vertical partition and a cover for said reserve compartment integral with a single sheet of material forming said body portion.

3. A combination packing and display container consisting of a body portion, a vertical partition dividing said body portion longitudinally into two compartments, namely, a display compartment and a reserve compartment, vertical partitions supported by and at right angles to said vertical partition dividing said body portion, said partitions dividing said display and reserve compartments into individual compartments or stalls 55 for each of the articles packed in said container, an aligning member integral with and composed of a cut out and perforated portion of the front of said display compartment adapted to be bent inward to

align the articles in both of said compartments and located above the bottom thereof, a cover for the top and front of said display compartment integral with said vertical partition adapted to be held in an upright position when opened to display advertising matter by means of integral wings or end pieces which lock into suitable slots in the ends of the reserve compartment, and a cover for said reserve compartment integral with a single sheet of material forming the body portion 70 of said container, said top and front cover for said display compartment rendering said reserve compartment invisible to the vendee when held in said open position.

4. A combined packing and display container comprising a first blank cut and bent to form a box with a horizontal aligning panel, spaced from the top and bottom of the box and provided with apertures, each adapted to receive and align a plurality of articles 80 placed one back of the other, and a second blank cut and bent to form, when placed in position in the box, a combined screen and cover to conceal when the box is open, the rearward articles positioned in said apertures.

5. A combined packing and display container comprising a first blank cut and bent to form a box with a horizontal aligning panel, spaced from the top and bottom of 90 the box and provided with apertures, each adapted to receive and align a plurality of articles placed one back of the other, and a second blank cut and bent to form when placed in position in the box, a combined screen and cover to conceal when the box is open, the rearward articles in said apertures, 95 said second blank having a dentilated edge to straddle the portions of the aligning panel between said apertures.

6. A combined packing and display container comprising a first blank cut and bent to form a box with a horizontal alining panel, spaced from the top and bottom of the box and provided with apertures, each adapted 105 to receive and aline a plurality of articles placed one back of the other, a second blank cut and bent to form when placed in position in the box, a combined screen and cover to conceal when the box is open, the rearward 110 articles in said apertures and a plurality of slotted vertical partitions engaging slots in the forward edge of said second blank when in the box to form a series of stalls for the articles placed thereon.

This specification signed this 9th day of June, 1926.

LEO EINSON.
